(57) **CLAIM**

The ornamental design for a speaker, as shown and described.

DESCRIPTION

FIG. 1 is a front perspective view of a speaker showing my new design;

FIG. 2 is a rear perspective view thereof;

FIG. 3 is a front view thereof;

FIG. 4 is a top view thereof;

FIG. 5 is a bottom view thereof;

FIG. 6 is an enlarged view of the encircled portion 6 indicated in FIG. 3;

FIG. 7 is a front view of a second embodiment of the speaker showing the new design, the only difference being the alternate speaker members in full lines;

FIG. 8 is a front view of a third embodiment of the speaker showing the new design, the only difference being the alternate speaker members in full lines; and,

FIG. 9 is a front view of a fourth embodiment of the speaker, the only difference being the consecutive speaker members in full lines.

The even length broken lines depict portions of the speaker that form no part of the claimed design. The dash dot broken lines encircling portions of the speaker in FIG. 3 and illustrated in the enlarged view of FIG. 6 form no part of the claimed design.
